UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

METHOD OF FORMING HEATED COMBUSTIBLE MIXTURES FOR INTERNAL-COMBUSTION ENGINES.

Application filed May 8, 1922. Serial No. 559,448.

This invention relates to internal combustion engines and particularly to methods of forming heated combustible mixtures for internal combustion engines.

5 The invention is particularly adapted for use in connection with engines for motor vehicles, motor boats, aircraft, etc., but it is not necessarily limited to such use.

10 The invention is particularly adapted to use the present low grade of gasoline, but it may also advantageously employ even lower grades of fuel, such as kerosene, as well as the higher grades or more volatile fuels.

15 In the use of internal combustion engines there are several problems which are due largely to the present low grade of gasoline. For instance, in cold weather an engine can be started only by supplying a very rich 20 mixture to the cylinders, the lighter fractions only of that mixture being ignitable in a cold state, and ordinarily it takes some time to bring an engine up to its full power because when cold it can burn only a small 25 proportion of the liquid fuel that is fed to it. This feeding of rich mixture to the engine and burning only a part of its fuel content has two very harmful results, first, it deposits carbon on the cylinder walls and 30 pistons and fouls the spark plugs, and second, much of the unburned fuel passes between the cylinder and piston walls, cutting the oil thereon, and collects in the crank case with the lubricating oil, thereby diluting the latter to an alarming degree. Therefore, if a cold engine is run for any 35 time on a rich mixture it soon becomes fouled with carbon and crank case oil dilution takes place to an extent that requires 40 frequent changing of the oil to prevent burning out of bearings and scoring of cylinders and pistons.

45 Also, a rich cold mixture is impossible of even distribution to the various cylinders of a multi-cylinder engine, because the heavier particles of the fuel will not take the turns in the intake passages as will the air and lighter particles and it is impracticable to provide intake passages from the carburetor to the several cylinders of exactly the 50 same form and length. The consequence is an uneven firing of the various cylinders and when one cylinder fires weakly or not

at all its following charge or charges will be still richer by reason of the unburned mixture remaining in it and it thereby tends to aggravate the situation instead of bettering it. This uneven firing is in itself most disagreeable in an automobile engine regardless of the injurious results that follow it.

55 The problems or difficulties above referred to are more particularly noticeable, of course, in cold weather. If the weather is not too cold the engine can usually be started by adjusting the carburetor to provide a very rich mixture. The mixture must then be continued rich until the engine warms up and itself supplies the mixture with heat by either heating the air entering the carburetor or heating the mixture passing from the carburetor to the motor, or both. Some engines employ the exhaust gases for this heating process and others use the hot water from the water jackets.

70 Engine exhaust and jacket water heaters obviously cannot supply initial heat to the carburetor or intake pipe and consequently are of no value in starting a cold engine. Initial electric heaters have been tried heretofore but with unsatisfactory results due to the large amount of current required to effect volatilization of the fuel. Combustion heaters have been tried prior to this invention but have not been found to be 75 thoroughly successful.

80 The present invention is of the combustion heater type and it contemplates forming, by the suction effect of the engine, a moving column of mixture of liquid fuel and air, separating a portion of the mixture which is thus being drawn into the engine, operating upon this separated mixture, through the suction effect of the engine, so that it will be readily ignited and burn 85 steadily and completely, igniting it, and then combining the hot products of combustion of the ignited mixture with the original column of mixture passing to the engine. This direct contact of the burnt gases with 90 the mixture passing through the intake pipe will quickly heat that mixture and the burnt and unburned gases will unite to form a heated combustible mixture that will 95 not condense on the walls of the intake pipe but will be evenly distributed to the vari-

ous engine cylinders and be readily ignited and fully burned there. It is one of the objects of the present invention to provide a method or process of forming this heated 5 combustible mixture that will distribute evenly and readily ignite and burn in an internal combustion engine.

Other objects of the invention will appear as the description proceeds.

10 The method forming the subject of this invention may take several different forms and, as will appear from the description, different mechanisms may be used to carry out the method. Several of such mechanisms are here illustrated for the purpose 15 of a full and clear understanding of the invention.

In the drawings:—

20 Fig. 1 is a vertical section through a carburetor, heater device and associated parts; comprising a mechanism by which the method may be practiced;

25 Fig. 2 is a cross section on the line 2—2 of Fig. 1;

30 Fig. 3 is a vertical sectional view showing another form of mechanism that may be used to carry out the method;

35 Fig. 4 is a section on the line 4—4 of Fig. 3;

40 Fig. 5 is a right end view of the elbow casting shown in Fig. 3, with parts broken away on the line 5—5 of Fig. 3; and

45 Fig. 6 is a vertical sectional view of another form of mechanism for practicing the invention.

50 Referring to the device shown in Figs. 1 and 2, 10 represents the float chamber of a carburetor, 11 is a passage leading from the float chamber to a fuel nozzle 12, 13 is a main air intake passage, and 14 is an auxiliary air intake passage of this carburetor. The passage 13 may be controlled by a butterfly valve 15 and the passage 14 is automatically controlled by a spring closed air valve 16. The nozzle 12 extends into a Venturi shaped mixing tube 17 the lower end of which communicates with the passage 13, and the tube in turn extends into a vertical mixing chamber 18 the lower end of which communicates with the auxiliary air passage 14. A throttle valve 19 controls the passage of mixture from the carburetor and an intake pipe 20 carries the mixture from the carburetor to the motor.

55 In operation, this carburetor maintains a desired level of fuel in the float chamber 10 by the usual operation of the float and valve therein, and the suction of the motor draws some of the fuel through the nozzle 12 and 60 also draws air through the passage 13 and tube 17 where it mixes with the fuel as both pass to the mixing chamber 18. As the suction of the motor increases the valve 16 is opened against its spring pressure and additional air is drawn into the mixture in

the chamber 18. The amount of mixture that passes to the motor is controlled by the throttle valve 19 which is shown as in its nearly closed position. Thus the suction effect of the engine forms a moving column 70 of mixture of liquid fuel and air upwardly through the tube 17 and chamber 18 and this column of mixture is controlled by the throttle valve 19. By manually controlling the tension of the spring of the valve 16 75 the richness of the mixture may be varied.

Above the mixing chamber 18, and shown as mounted on the intake pipe 20, is a closed chamber 21 which may be termed a combustion chamber. It is separated from the intake pipe 20 by a corrugated wall 22 so that some of the heat of the combustion chamber 80 may be readily transferred to the intake conduit or pipe.

85 A pipe or conduit 23 having its inlet in the form of a narrow slot 24 within the mixing chamber 18, is adapted to withdraw from said chamber some of the mixture therein. The other end of the conduit 23 is connected with the chamber 21 as shown at 90 25, a fine mesh screen 26 being arranged over the pipe connection so that the mixture entering the chamber 21 will be broken up as it enters the chamber. An outlet pipe or conduit 27 extends from the chamber 21 95 to the intake conduit 20 above the throttle valve 19. This connection is shown at 28 and the outlet connection from the chamber 21 is shown as covered by a screen 29.

100 The chamber 21 has an air inlet port 30 which may be controlled either by a spring closed air valve 31 or by a manually controlled valve 32, or both. This port is provided to supply additional air to the mixture if a richer mixture than is required is 105 supplied by the mixture withdrawing means 23.

110 A spark plug 33, suitably connected with the ignition system of the motor is arranged with its sparking points in the chamber 21 for firing the mixture as it enters therein.

115 From the above description it will be seen that the suction of the engine in the intake pipe 20 will act through the pipe 27, the chamber 21 and the pipe 23 to withdraw part of the moving column of mixture from the mixing chamber 18 and thus form a separate column of mixture in the pipe 23. This is particularly so when the throttle valve 19 is partly closed as at that time the suction is greater in the pipe 23 than it is in the chamber 18 below the throttle valve.

120 This separated column of mixture in the pipe 23 is thus speeded up and as it enters the chamber 21 it is broken up by the screen 26. It is ignited by the spark plug 33 and the products of combustion pass out through the pipe 27 into the intake conduit 125 130

20 where they mix with the original column of mixture passing to the motor.

Thus the suction of the engine, whether running under its own power or being cranked by an electric or other starting motor, causes the carburetor to deliver an upwardly moving column of mixture to the chamber 18, and this column of mixture, particularly with the throttle valve partly closed, is divided or separated into two columns, one continuing on to the engine through the intake conduit and the other taking a path through the pipe 23. The high suction in the pipe 23 speeds up the mixture therein thus agitating it, and the screen 26 breaks it up as it enters the chamber 21. Here ignition takes place and while some of the heat of combustion is transferred through the corrugated wall to the intake pipe, the greater part of it is carried through the pipe 27 with the products of combustion directly onto the intake conduit 20 where the burnt gases combine with the column of mixture passing therethrough to the engine. The fresh mixture is thereby heated and prevented from condensing on the relatively cold wall of the intake conduit, and a mixture that will readily ignite and burn completely is delivered to the engine for starting and operating it. Thus an even distribution of mixture to the cylinders is insured and as the mixture will be fully burned there will be no appreciable carbon deposit or dilution of the crank case oil.

Referring to the device shown in Figs. 3, 4 and 5, the lower part of the carburetor is not shown because it is exactly like that shown in Fig. 1. The fuel nozzle 12, however, is illustrated as is also the mixing tube 17 and the mixing chamber 18. Likewise, the throttle valve 19 and the engine intake pipe 20 are shown. In Fig. 3 the motor cylinder block is indicated at B, the intake pipe 20 being connected to the cylinder block.

In this as in the previously described device the mixing chamber 18 and the intake pipe 20 merge into each other and in Fig. 3 this chamber or passage is shown in elbow form and the combustion chamber 21 is an integral part of the elbow. The inlet 40 for the conduit 41 leading to the combustion chamber 21 is situated in the turn of the elbow where it will readily separate and receive a part of the mixture from the carburetor. The conduit 41 leads upwardly to a transverse port 42 which enters a vertical passage 43 somewhat tangentially thereof, as shown particularly in Fig. 4. The passage 43 extends downwardly and a screen 44 is arranged between it and the spark plug 33 and by this means the separated portion of mixture is given a whirling motion in the passage 43 and is thereby agitated and

broken up, passing through the screen 44 into the combustion chamber 21 near the spark plug 33. The spark plug fires this readily ignitable mixture and the products of combustion pass out through a port 45 leading into the intake conduit 20 between the throttle valve 19 and the engine cylinders. The products of combustion thereby mix with the moving column of mixture passing from the mixing chamber 18 through the intake conduit 20 to the engine.

An air port 46, adjustable as to size by the thumb valve 47, is arranged in the conduit 41 so that the mixture may be leaned out slightly if desired. A glass window 48 is also provided to observe the firing action.

One of the features of the invention that is particularly well practiced by this device is that of speeding up and agitating the separated portion of the mixture. The port 45 being large and entering the intake conduit beyond the throttle valve, and the port 42 being small and tangentially directed, there is considerable of a pull on the mixture when the throttle valve is in nearly closed position and the mixture is consequently caused to flow rapidly through the conduit 41 and port 42 and it is greatly agitated and broken up as it travels from that port to the vicinity of the spark plug in the combustion chamber. The result is a beautifully steady burning flame in the combustion chamber and its very hot products of combustion are rapidly drawn off through the large port 45 into the intake conduit 20 where they mingle with the other portion of the original mixture column and heat it and travel with it as a combined mixture evenly distributed to the various cylinders of the engine.

Referring to the devices shown in Fig. 6, the float chamber 10, passage 11, main air passage 13, auxiliary air passage 14, mixing tube 17 and mixing chamber 18 are similar to like parts in Fig. 1. The fuel nozzle 50, however, is somewhat different in that it is formed with a plurality of outlets, the lower outlet 51 being arranged in the neck of the choke tube 17 and the upper outlet 52 being arranged somewhat nearer the top of the tube. The operation of the device, however, is substantially the same except that a somewhat leaner mixture is provided under certain working conditions of the motor and an economy in the use of fuel is effected. Both devices furnish a substantially uniform mixture of fuel and air throughout the running range of the engine.

The throttle valve 19, so far as its valve function is concerned, is also the same as that shown in the other views and the intake pipe 20 above the throttle valve leads to the motor cylinder block B as previously explained.

In the present instance a portion of the mixture is withdrawn from the mixing

- chamber 18 through one or a series of ports 53 and a conduit 54 formed in the throttle valve 19 and its shaft. The conduit 54 connects at one of its ends with a pipe 55 which leads through a contracted port 56 and a vertical passage 57 into the combustion chamber 21. The port 56 is also slightly offset as is the port 42 of Fig. 3, so that the mixture whirls downwardly through the passage 57 and through a screen 58 into the combustion chamber 21 where it is ignited by the spark plug 33 as before.
- An outlet conduit 59 leads from the combustion chamber 21 to a port 60 communicating with the intake conduit 20 above the throttle valve 19 so that the suction of the intake conduit performs its function of drawing a part of the mixture from the mixing chamber 18 through the pipe 55 and into the combustion chamber 21 as in the previously described constructions. The conduit 59 and port 60 are larger than the port 56 so that the smaller column of mixture is speeded up in its passage.
- There is also an adjustable air intake port 61 communicating with the combustion chamber 21 through a channel 62 for the purpose of obtaining a closer regulation of the mixture.
- In this device of Fig. 6 the carburetor, by the suction effect of the engine, delivers a vertically moving column of mixture of liquid fuel and air to the chamber 18 in which the throttle valve 19 is located; a relatively small portion of this mixture is separated from the main column and drawn through the ports 53 and conduit 54 into the pipe 55. This smaller or secondary column is speeded up as it passes through the small port 56 and in the passage 57 it is given a whirling motion and passed through the screen 58 in a finely divided state. This mixture enters the chamber adjacent the spark plug and is fired thereby. If it is too rich it will burn lower down in the chamber by reason of the admission of air to that part of the chamber and the products of combustion will pass out through the port 60 into the intake conduit 20. Here the burnt gas combines with the original column of mixture and a hot mixture is formed that will be carried through the conduit 20 into the engine without material condensation on the walls of the intake pipe.
- Having thus described my invention, what I claim and desire to secure by Letters Patent is:—
1. The method of forming a heated combustible mixture for internal combustion engines, said method consisting in forming, by the suction effect of the engine, a moving column of mixture of liquid fuel and air, separating said mixture into two columns, agitating the mixture of one of said separated columns, moving said agitated mixture col-

umn vertically over an electric spark and thus igniting the mixture of said agitated column, and then combining the hot products of combustion of the ignited mixture with the other separated column of mixture. 70

2. The method of forming a heated combustible mixture for internal combustion engines, said method consisting in forming, by the suction effect of the engine, a moving column of mixture of liquid fuel and air, separating said mixture into two columns, speeding up the movement of and agitating the mixture of one of said separated columns, igniting the mixture of said agitated column, and then combining the hot products 75 of combustion of the ignited mixture with the other separated column of mixture. 80

3. The method of forming a heated combustible mixture for internal combustion engines, said method consisting in forming a 85 moving column of mixture of liquid fuel and air, separating said column into two columns of mixture, agitating the mixture of one of said separated columns and mechanically dividing the fuel particles thereof, igniting 90 the mixture of said agitated column, and then combining the hot products of combustion of the ignited mixture with the other separated column of mixture.

4. The method of forming a heated combustible mixture for internal combustion engines, said method consisting in forming a moving column of mixture of liquid fuel and air, separating a relatively small portion and thus forming a secondary column 100 of mixture from the primary column, agitating the mixture of said secondary column and mechanically dividing the fuel particles thereof, igniting the mixture of said secondary column, and then combining the hot 105 products of combustion of the ignited mixture with the primary column of mixture.

5. The method of forming a heated combustible mixture for internal combustion engines, said method consisting in forming a 110 moving column of mixture of liquid fuel and air, separating a relatively small portion and thus forming a secondary column of mixture from the primary column, moving said secondary column of mixture substantially vertically downwardly over an electric spark and thus igniting the mixture of said secondary column, and then combining the hot 115 products of combustion of the ignited mixture with the primary column of mixture. 120

6. The method of forming a heated combustible mixture for internal combustion engines, said method consisting in forming a moving column of mixture of liquid fuel 125 and air, separating a relatively small portion of said mixture and forming it into a downwardly moving substantially vertical secondary column and admitting air to the mixture at the lower part of said column, 130

igniting the mixture of said secondary column above the point of air admission, and then combining the hot products of combustion of the ignited mixture with the primary column of mixture.

7. The method of forming a heated combustible mixture for internal combustion engines, said method consisting in forming a moving column of mixture of liquid fuel and air, separating a relatively small portion of said mixture and forming it into a downwardly moving substantially vertical secondary column and admitting air to the mixture at the lower part of said column, igniting the mixture of said secondary column, and then combining the hot products of combustion of the ignited mixture with the primary column of mixture.

8. The method of forming a heated combustible mixture for internal combustion engines, said method consisting in forming, by the suction effect of the engine, a moving column of mixture of liquid fuel and air, separating a relatively small portion of said mixture and, by said suction effect, forming it into a more rapidly moving secondary column and admitting air to the mixture thus separated, igniting the mixture of said secondary column, and then combining the hot products of combustion of the ignited mixture with the primary column of mixture.

9. The method of forming a heated combustible mixture for internal combustion engines, said method consisting in forming, by the suction effect of the engine, a moving column of mixture of liquid fuel and air, separating a relatively small portion of said mixture and thus forming a secondary column of mixture from the primary column, speeding up the movement of and agi-

tating the mixture of said secondary column by said suction effect, igniting the mixture of the secondary column, and then combining the hot products of combustion of the ignited mixture with the primary column of mixture.

10. The method of forming a heated combustible mixture for internal combustion engines, said method consisting in forming, by the suction effect of the engine, a moving column of mixture of liquid fuel and air, separating a relatively small portion of said mixture and thus forming a secondary column of mixture from the primary column, speeding up the movement of and agitating the mixture of said secondary column by said suction effect and mechanically dividing the fuel particles of the mixture of said secondary column, admitting air to the mixture of said secondary column at the lower part thereof, igniting the mixture of said secondary column above the point of air admission, and then combining the hot products of combustion of the ignited mixture with the primary column of mixture.

11. The method of forming a heated combustible mixture for internal combustion engines, said method consisting in forming, by the suction effect of the engine, a moving column of mixture of liquid fuel and air, separating the mixture into primary and secondary columns, the former of which is larger than the latter, speeding up the movement of the mixture of the secondary column, igniting the speeded-up mixture of the secondary column, and then combining the hot products of combustion of the secondary column with the mixture in the primary column.

In testimony whereof I affix my signature.
LIONEL M. WOOLSON.
